CLAIM

We claim the ornamental design for a punch insert substantially, as shown and described.

DESCRIPTION

FIG. 1 is a perspective view of a punch insert showing our new design;

FIG. 2 is a top plan view thereof;

FIG. 3 is a second perspective view thereof;

FIG. 4 is a bottom plan view thereof;

FIG. 5 is a rear elevation view thereof;

FIG. 6 is a left side elevation view thereof;

FIG. 7 is a front elevation view thereof; and,

FIG. 8 is a right side elevation view thereof.

The broken lines in the figures represent portions of the article which form no part of the claimed design.
